UNITED STATES PATENT OFFICE.

JAMES HOOVEN, OF NORRISTOWN, PENNSYLVANIA.

MACHINE FOR SCARFING AND BENDING TUBE-SKELPS.

SPECIFICATION forming part of Letters Patent No. 416,731, dated December 10, 1889.

Application filed July 2, 1889. Serial No. 316,314. (No model.)

To all whom it may concern:

Be it known that I, JAMES HOOVEN, a citizen of the United States, residing at Norristown, in the county of Montgomery and State 5 of Pennsylvania, have invented certain new and useful Improvements in Machines for Scarfing and Bending; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 Figure 1 is a plan view of the device. Fig. 2 is a side view. Fig. 3 is a detail looking in the direction of the arrow on line 3 3, Fig. 2. Fig. 4 is an enlarged detail looking in the direction of the arrow on line 4 4, Fig. 2, parts 20 being broken away, the dotted lines showing parts beyond. Figs. 5 and 6 are edge and side views of the guides along the sides of the device. Figs. 7 and 8 are plan and end views 25 of the transverse guide-plates for the side guides. Fig. 9 is an enlarged front end view of the device. Fig. 10 is a section on line 10 10, Fig. 11. Fig. 11 is an inside view of the cutters. Figs. 12 and 13 are plan and edge views of the knives of the scarfing-cutters. 30 Fig. 14 is an enlarged side view with parts broken away, so as to show the guides. Fig. 15 is a top view, partly in section. Fig. 16 is a perspective of a side guide; and Fig. 17 is a section on line 17 17, Fig. 16.

35 This invention relates to improvements in skelping - machines such as are shown in patents granted to me March 23, 1880, No. 225,835, and June 30, 1885, No. 320,936. In the machines set forth in these patents the 40 skelp is bent so as to be ready for welding; but with these machines only a butt-weld can be made. To have a weld with a scarf-joint it is necessary to scarf the skelp in the usual way before presenting it to the rolls. 45 By the present invention the scarfing and bending are performed at one operation, and when the bent skelp comes from the machine it is all ready for a lap-weld.

In the annexed drawings, the letter A indicates the bed of the scarfer, and B that of the bender, which may be in one piece, being in line, as shown. Bolted to and rising from

the bed A are the pairs of standards C, D, E, and F, the first three being near together, the last two somewhat spaced apart, as at a. In 55 these standards are placed the boxes c c' d d' e e' f f'. In these boxes are journaled the shafts of the feeding-rollers C' C² D' D² E' E², of which there are three sets, and the set of withdrawing - rolls F' F². As these rolls are 60 constructed alike, a description of one set will suffice. The upper roll C' consists of three disks c c' c², the lower roll C² of three disks c² c' c², internally screw-threaded and placed upon the threaded shafts c³ and c⁴, the former 65 above, the latter below, and are held in any given position by the jam-nuts c⁵ c⁶ c⁷. The middle disk c' may be narrower than the others and is the same size and shape in both the upper and lower rolls; but the lower disks 70 c², while they are of the same size as the upper disks c, they have on the outside, flanges c⁸.

The standards C, D, E, and F have on each side a bracket b. Secured to these brackets between the standards C and D and D and E, in front of the standard C, at the rear of the standard E, and in front and rear of the standard F, are the transverse guide-plates G. (Shown enlarged in Figs. 7 and 8.) 75 These plates when used between the standards have the pairs of wings g g', by which they are bolted to the brackets. When used only at front or rear, they have only the wings on the side next to the standard. These 80 guide-plates have the transverse angular groove g² in their tops and the slots g³, and the hole g⁴ at the middle between the slots. These slots are to receive the pins h of the 85 side guides H, such as shown in Figs. 5 and 6 and in end view in Fig. 9. These guides consist of the flat base h', from which rise the sides h², which flare outwardly toward the sides of the machine, the flare of these sides h² being the same as that of the flanges of 90 the other disks of the lower rolls already described. At each end of the guides there is made a notch h³, as shown. These guides have the projections h⁴ on the outside, provided with the tongues h⁵, and they are put 95 into position with these tongues h⁵ in the grooves g² of the transverse guide-plates G, and are held in any position by the pins h. The length of these guide-plates is such that 100

their flaring edges form a practical continuation of the flanges of the outer disks of the lower rolls, the shape of the notches g^2 permitting the guides and disks to come close together.

The construction already described produces feed-rolls and guide-plates which are readily adjustable for varying widths of skelps, and at the same time preserves a continuous 10 guide on each side of the skelp, keeping it true and steady.

In the holes g^4 of the guide-plates G is secured a strip G' , which is in line with the middle disks of the feed-rolls.

15 In the space a , between the standards E and F, there is secured to the base B, on each side, a supporter I. Engaging this supporter I, by an ordinary tongue and groove, is the block K, and through these blocks passes the 20 right and left hand threaded rod k , having the wheel or crank k' . Rising from these blocks K are the open frames L, having the bearings $l l'$ at their tops and bottoms. In these bearings are journaled the scarfing-cutters M. The plate m of the cutters is made 25 in the general shape of the frustum of a cone.

Just inside of the rim m^3 there is a circumferential rabbet m^3 , and the edge m^4 runs in toward the center as a bevel to the point m^5 ; 30 then, thence to the center the surface m^6 is flat and parallel with the outer face of the plate m . Beyond this surface m^6 projects the box m^7 , forming a shoulder m^8 . Running from this box m^7 to the rim m^3 are angular 35 radial grooves m^9 . Within these grooves are placed the scarfing-knives N. These knives are fitted to the grooves, being of the same shape, but somewhat larger. They have the straight body portion n and the beveled cutting-edges n' . Their straight edges n^2 project 40 beyond the faces m^6 , their ends n^3 rest in the rabbet m^3 , and their cutting-edges n' extend beyond the edges m^4 . The edges n' are not only beveled outwardly, so as to scarf, but 45 they are beveled from front to back, so as to have a sharp cutting-edge. When these knives N are in place, they are secured by a retaining-disk O, which slips over the box m^7 , bears against the edges n^2 of the knives, 50 and is held securely in place by the bolts o, which pass through it and the plate M. These cutters are threaded upon the vertical journals P, and held in position by the jam-nuts p, the journals having bearings in the frame 55 L, and at their tops the beveled wheels p' . Rising from the tops of the frames L are the brackets p^2 , in which is journaled the shaft p^3 , carrying by a sliding connection the wheels p^4 , which are beveled and engage the wheels 60 p' . These wheels p^4 are engaging with the brackets p^2 , so that they are rotatable in said brackets, but can move with them along the shaft p^3 .

As shown in Fig. 4, the cutters M are put 65 into place so that they are in reverse position on opposite sides—that is, the edges n^2 of the knives project in opposite directions.

As clearly indicated in the drawings, the bending portion of this machine is identical with that shown in the patents referred to, 70 except that an additional set of benders has been introduced so as to specially adapt the machine for bending skelps where the edges are scarfed, and thus form a lap-joint.

In the machines already patented to me, 75 which prepared the skelp for a butt-weld, it was necessary only to bend the strip so that its edges would be turned over toward each other and meet without passing; but to form a lap-weld the edges must pass each other. 80 Therefore to adapt my machine to preparing the skelp for a lap-weld, I have added to it the peculiar kind of bending-rolls shown in detail in Fig. 3. In this pair one roll—the upper R, as shown—has the usual semicircular 85 peripheral groove; but the peripheral groove s, in the lower roll S, is made with one side s' more abrupt or nearer the vertical than the other s², thus bringing the edge s³ within the edge r⁴ of the upper roll. The last pair of 90 rolls T and U of the machine have the usual semicircular peripheral grooves.

In use the strip is fed to the feeding-rolls at the front of the machine and is held firmly in place by them, the flanges c^8 of the 95 lower outer disks c^2 and the edges h^2 of the side guides H keeping the strip true. The feeding-rolls and the withdrawing-rolls are driven in any suitable manner—such, for example, as by a chain, as shown in Fig. 1—100 positive power being applied to one pair. The scarifiers are driven by positive power applied to them. As the strip meets the cutters M, these revolving against it scarf the edges of the strip, as clearly indicated in Fig. 105 4, the strip in passing from the cutters being secured and held firmly by the withdrawing-rolls. From these it is passed to the bender, where the usual operation takes place. As the bent strip reaches the pair of rolls R and 110 S, the shape of the groove s in the lower roll S turns the lower edge of the strip within the upper edge, thus causing them to lap. As they pass between the rolls T and U, the edges are pressed together, the tube being 115 given the circular form, the edges thus being put into condition for a lap-weld. Such a machine, scarfing and bending the skelp at one operation, simplifies, cheapens, and expedites the operation.

120 The machine is also adapted for strips of varying widths, as the disks of the rolls and the guides can be moved in and out.

Having thus described my invention, what I claim is—

1. The combination of the feed-rolls, the scarfing-cutters independent in their action, and the bending-rolls, as set forth.
2. The combination of the scarfing-cutters and the bending-rolls, one roll of one pair of bending-rolls having one edge of the groove in its periphery within the corresponding edge of the groove of its companion roll, as set forth.

3. The feeding-rolls consisting of the adjustable disks, as set forth.

4. The combination of the guides H, consisting of the base h' and flaring edges h^2 , with the outer disks $c^2 c^3$, of the lower feed-rolls, such disks having the flanges c^8 , the edges h^2 and flanges c^8 being in line, as set forth.

5. The transverse guide-plates G, having the slots, groove g^2 , and slots g^3 , in combination with the guides H, having the projection h^4 , provided with the tongue h^5 , and the bolt h , as set forth.

6. The combination of the supports I, the blocks K, carrying the cutter - supporting frames, and the right and left hand threaded rod h , as set forth.

7. The supporting-frames L, in combination with the cutters M, having the journals P, which bear in said frame and have the bevel-

wheels p' , the shaft p^3 , and its beveled wheels p^4 , with the brackets p^2 , as set forth.

8. The cutter M, consisting of the plate m , having the radial grooves m^9 , the box m^7 , and rim m^2 , there being a rabbet m^8 within said 25 rim, the knives N, held in the grooves, but projecting beyond the edges thereof, the retaining-disk O, and the bolts o, as set forth.

9. In a skelp-bending machine for preparing the skelp for a lap-weld, a pair of rolls 30 having peripheral grooves, one edge of the groove of one roll being within the corresponding edge of the groove of the companion roll, as set forth.

In testimony whereof I affix my signature in 35 presence of two witnesses.
